LINED CARTON

Herbert J. Stotter, Shaker Heights, Ohio

Application May 1, 1941, Serial No. 391,318

1 Claim. (Cl. 229—14)

1

This invention relates to an improvement in lined cartons and a method of making them, and, more particularly, to a method of making and lining a standard four side carton upon standard carton machinery with a liner of heat-sealable material and a lined carton made by this method, the liner in the carton being so arranged and constructed that its open mouth may be easily flattened to be securely sealed.

The well-known standard paper board or cardboard cartons, in which substantially all mass-production merchandise is sold, are the so-called "four sided" cartons which are comprised of a front panel, a rear panel, side panels, glue lap, and end flaps formed from an integral blank characterized by four parallel longitudinal score lines which define the front, rear, and side panels and the glue lap. Although ingenious scores and cuts in the carton blank may vary the ultimate appearance of the carton, the overwhelming majority of all cartons are basically four-sided. This is both the cause and result of the automatic carton machines used in substantially all of the numerous carton plants being substantially standardized. The ultimate objective in manufacturing lined cartons, therefore, has been to invent a method which would permit a lined carton to be made in a standard carton machine without altering the construction of the machine or its sequence of operations, but by simply adding a simple element and interposing the operation of the added element so that it would not interfere with the standard operations. This invention achieves that objective.

Heretofore, any lined cartons which have been susceptible of manufacture on any sort of automatic machinery, standard or otherwise, have not been entirely satisfactory because of the location and arrangement of the longitudinal seam which forms the liner sheet into a tube. The form of the longitudinal seam in the liner presented a particularly difficult obstacle to overcome when it was attempted to heat-seal the open mouth of a filled carton. The two types of longitudinal liner seam used heretofore were either a lap seam or a face-to-face seam on a reversely turned fin. The lap seam itself could not be heat-sealed and the extra thickness of the liner at the lap made heat-sealing of the mouth of the liner difficult. The face-to-face seam on a reversely turned fin could be heat-sealed, but, to seal the mouth of this type of liner, the reversely turned fin must be unfolded to obtain a seal without reentrant folds or extra thicknesses of material. This renders such lin-

2

ers with a reversely turned fin difficult to use in automatic or semi-automatic sealers, particularly in the case of four-sided cartons where the fin is located at the corner of the carton and thus requires a flat seal at the mouth of the liner to extend diagonally of the erected carton. All of the foregoing objections are overcome by this invention which provides a liner with a substantially butt-welded longitudinal seam detectable only by the presence of a fine longitudinal bead which is so small that it does not interfere with the sealing of the mouth of the liner. In a lined four-sided carton made according to this invention, longitudinal fins on the liners are eliminated and the mouth of the liner may be sealed along a line parallel to the front and back panels of the carton in an automatic or semi-automatic heat-sealer.

Another object of this invention is to provide a lined carton in which the inner liner, though formed from a flat liner sheet attached to a flat carton blank and, consequently, formed simultaneously with the formation of the flat blank, may be pulled out of the completed carton as a separable bag element. Heretofore, in lined cartons in which the liner constituted a separable bag element, the liner was a preformed bag around which the carton was formed or a pre-formed bag inserted into the completed carton. My invention eliminates the heretofore necessary bag preforming operation.

Other objects and advantages of this invention will be apparent from the following specification, claim and drawings, in which:

Fig. 1 is a plan view of a flat four-sided carton blank with a liner sheet attached.

Fig. 2 is a plan view of the carton blank shown in Fig. 1 after the first folding operation and illustrating the formation of the longitudinal side seams in the liner.

Fig. 3 is an elevation of a completed collapsed flat tubular lined four-sided carton formed from the blank shown in Fig. 1 but with bottom flaps turned up to show the bottom mouth of the liner sealed.

Fig. 4 is a top view of a four-sided carton erected from the collapsed condition shown in Fig. 3 and illustrating the manner of flattening the mouth of the liner.

In the drawings, which disclose one form of a four-sided carton embodying my invention, 10 represents the blank of cardboard, pasteboard, corrugated paperboard, or like paper stock from which the outer shell of the lined carton is made.

55 In the carton blank, visible edges and cuts are

shown in heavy solid lines, invisible (i. e., viewed through the liner) cuts and edges are shown as light single dash lines, visible score lines are shown as heavy double dash lines, and invisible score lines are shown as light double dash lines. Between the parallel longitudinal edges 11 and 12 of the blank 10 are the four parallel longitudinal score lines 13, 14, 15, and 16. The spaced top fold line 17 and bottom fold line 18, which may be completely scored or partly cut and scored, as the end flap construction requires, are parallel to each other and extend at right angles to the longitudinal score lines. The top and bottom lines and the longitudinal edges and score lines define the glue lap 21, front panel 22, left side panel 23, back panel 24 and right side panel 25, as shown in Fig. 1, the front and back panels being of equal width but the glue lap being narrower than the side panels, which are of equal width.

The bottom closure in the carton made from the blank 10 shown in Fig. 1 is designed to be provided with a sealed end closure. The blank 10, therefore, is provided with the customary sealing flaps 31, 32, 33, and 34 integral with the glue lap and panels 21, 22, 23, and 24, respectively, along the bottom fold line 18. The top closure of the carton made from the blank 10 is designed to be provided with a tuck-in closure. The blank 10, therefore, is provided with the customary side flaps 41 and 43 and tuck-in flap 44 integral with the glue lap 21, side panel 23, and rear panel 24, respectively, along the top fold line 17. The end-closures described above are merely described by way of example, the particular style of end-closure or arrangement and location of the end flap being more or less immaterial to this invention. It is preferred, however, that the panel inside the side score line (i. e., toward the center of the blank with respect to the side score line, the line 16 being the side score line in this disclosure) be provided with both top and bottom flaps, and that the outside edges of these flaps be continuations of the side score line. It is also preferred that the top and bottom score lines, at least adjacent the side score line be cut scores rather than creased or pressed scores, and, further, that these top and bottom flaps extend to or slightly beyond the top and bottom edges of the liner sheet.

The liner sheet 50 is of such a length that it will extend beyond the top and bottom fold lines a sufficient distance to permit the top edge and the bottom edge to be sealed when the carton is formed and erected. The width of the liner sheet 50 is such that, when placed upon the blank 10, one longitudinal margin will extend beyond and outside the side score line and the other longitudinal margin will extend outside and overhang the longitudinal edge of the blank oppositely disposed with respect to the side score line. Thus, in the blank shown in Fig. 1, one longitudinal edge 51 of the liner sheet 50 overhangs the longitudinal edge 11 of the blank 10 to provide a margin 52 and the other longitudinal edge 53 of the blank 50 extends beyond and outside the side score line 16 to provide another longitudinal margin 54. The liner sheet 50 is adhered to the blank 10 by means of suitable areas of adhesive 61, 62, 63, and 64 applied to the glue lap and panels 21, 22, 23, and 24, respectively. Additional spots or lines of temporary adhesive 66, 67, and 68 may be applied to the end flaps 44, 41, and 34, respectively, to temporarily adhere the top corners and the bottom corners of the liner sheet 50 to the several flaps adjacent the longitudinal

5 margins 52 and 54 during the fabrication of the carton in standard carton machinery. The liner sheet 50 is composed of heat-sealable sheet stock, which is also water-proof or moisture-proof, and 10 may also be oil-proof, depending upon the needs and characteristics of the product being packaged. Examples of sheet stock meeting the requirements of the liner sheet 50 are rubber hydrochloride film, such as the rubber hydrochloride film known commercially as "Pliofilm," polyvinyl resin film, such as the polyvinyl chloride and/or polyvinyl acetate film known commercially as "Koroseal" or "Vinylite," cellulose acetate, or any other thermoplastic film which will seal or weld under heat and pressure. The liner sheet 50 may 15 also consist of a paper backing sheet provided with an inner (with respect to the complete carton) surface laminated or coated with thermoplastic heat-sealing material, such as a natural or synthetic thermoplastic heat-sealing resin and/or a plasticizer. In any event, the lining sheet 50 should be thin enough so that two thicknesses may be cut through by a knife against the blank 10 or against a cooperating metal anvil as the carton blank passes through a gluer in a standard carton machine set-up.

To fabricate my carton in standard carton machinery, the blank 10 is first cut out of suitable board sheet stock in any suitable die-cutter. The die-cut flat blank 10 is then run through a standard window pasting machine which spots the several areas of adhesive 61, 62, 63, 64, 66, 67, and 68 upon the blank 10 and substantially simultaneously cuts off the liner sheet 50 from a roll of liner stock and applies the liner sheet 50 to the blank 10, to form the combined blank and liner sheet as shown in Fig. 1.

The combined blank 10 and liner sheet 50 is then passed through a standard gluer which first applies the longitudinal band of adhesive 65 to the side panel 25 by means of a glue wheel or similar standard adhesive applying means. The combined blank and liner is then folded along the central score line 14 so that the glue lap 21 overlies the back panel 24 and at least a portion of the longitudinal liner margin 52 will overlie the liner margin 54 in substantially face-to-face contact, the margin 52 being wide enough so that the longitudinal edge 51 of the liner 50 will extend outside and beyond the side score line 16 when the combined carton blank and liner are so folded, as shown in Fig. 2 of the drawings.

Up to this point, the operation and procedure have been the standard and conventional ones in the manufacture of standard four-sided cartons, except insofar as the liner sheet 50 is located somewhat differently from and is larger (in proportion to the size of the blank 10) than the window of transparent film normally applied in a standard window machine. It is also novel practise to provide the preferred spots of temporary adhesive 66, 67, and 68. Even these exceptions to standard practise do not require alterations in the window machine or changes in procedure but merely require a slightly different setting of the sheet cutting and spotting elements of the machine. At this point, however, is interposed the additional step in the otherwise substantially standard procedure and an additional element must be added to a standard gluer. With the folded carton blank passing through the gluer in the direction indicated by the directional arrow in Fig. 2, it passes under a sealing and cutter element 70 which trims off the margins 52 and 54 and heat-seals the liner sheet 50 together

along a longitudinal seam 71 to form the liner sheet 50 into a tube. It is also this point at which the preferred spots of temporary adhesive 66 and 67 serve their function. Because the feeding tapes run continuously in a standard gluer, thus moving the blanks uninterruptedly through the machine, heat-sealing and cut-off element 70 is held stationary by fastening it to a suitable fixed member in the machine, the folded blank being dragged under, i. e., through, the heat-sealing and cut-off element by the feeding tapes. If the heat-sealing and cut-off element 70 is simply a stationary heated knife, as shown in Fig. 2, the liner sheet margins 52 and 54, being free and loose from the blank 10, would ruck up as the forward edge of the liner sheet 50 was engaged by the heat-sealing and cut-off element 70. This tendency of the loose liner margins to ruck may be minimized by having the element 70 comprised of a heated wheel provided with a sharp knife edge, or a heated narrow-rimmed wheel which first engages and heat-seals the overlying plies of the liner sheet and a knife immediately following the heated narrow-rimmed wheel, which cuts through the heat-seal and trims off the margins 52, and 50, or by mounting the element 70 so that it is normally raised but is lowered into engagement with the blank by a suitable timer, such as an electric eye timer, for example, just as the forward edge of the liner 50 passes under the element 70. Regardless of which one of the suitable heat-sealing and cut-off elements may be employed, the tendency of the forward edge of the liner sheet 50 to ruck up is prevented by providing the spots of adhesive 66 and 67 which adhere the forward edge of the liner sheet 50 adjacent the margins 52 and 54 to the relatively stiffer flaps of the blank 10. Thus, as the heat-sealing cut-off element engages the forward edge of the liner sheet 50, the liner sheet will be held and prevented from rucking and wrinkling. If the heat-seal and cut-off is started correctly, there is no especial tendency for the plies of the liner sheet 50 to ruck up thereafter, particularly if the bottom ply is secured to the blank 10 adjacent the seam 71, as by the area of adhesive 64, for example.

It should be particularly noted that the seam 71 is formed on or just inside the side score line 16. Thus, no reversely turned fin will be formed when the carton is completed and erected, and yet the seam in the liner will be substantially supported by the corner which is formed in erecting the carton and folding the blank along the longitudinal side score line 16. When it is stated hereinafter that the longitudinal seam in the liner is formed "at" the side score line, it is to be understood that the seam is located on or just inside the side score line.

By providing the panel inside the side score line with flaps having outside edges which are extensions of the side score line, it is usually possible to cut through the superimposed plies of the liner sheet against the blank throughout the length of the longitudinal seam in the liner sheet. Also, by cut-scoring the portions of the laterally extending score lines which the longitudinal liner seam crosses, there are no creased score lines which the element 70 must ride over in forming the seam 71. Such creased score lines could cause the element 70 to jump and fail to form the seam 71 at the lateral score lines. However, in the event that the carton blank is not provided with top and bottom flaps having outside edges which are extensions of the side

score line, or in the event that the stock in the blank is too soft to permit the element 70 to heat-seal and cut-off the liner 50 directly against the blank, the element 70 may be provided with a thin metal anvil which will slip between the overlying liner and the blank to permit the element 70 to cut and heat-seal the liner against the hard surface of the anvil rather than against the soft surface of the blank.

It should also be pointed out that the seam 71 is very narrow, being preferably about as wide as the thickness of one ply of the liner sheet. Thus, the seam 70 is substantially a butt joint rather than a wide face-to-face joint. Because the inner surfaces of the liner are actually welded together at the seam 71, the seam is as strong as the liner material and just as strong as the wide lap or face-to-face seams, believed to be necessary heretofore, could be. In the drawings, the width of the seam 71 is exaggerated for purposes of illustration. Actually, the seam 71 may be scarcely perceptible, being noticeable only as a slight bead on the outer surface of the tubed liner sheet.

After the longitudinal seam 71 is formed, the remainder of the operations in forming the lined carton are standard operations performed in standard carton machinery. After the longitudinal seam 71 is formed, the next operation in the gluer is that of folding over the side panel 25 along the side score line 16 and adhering the panel 25 to the glue lap 21 by means of the band of adhesive 65. This operation, in the formation of standard unlined four-sided cartons, normally follows immediately after the operation of folding the blank along the central score line.

After the blank has passed through the gluer, it is in the form of a flat collapsed lined tube. In most instances it may be regarded as being complete for sale to the user. However, some users may want the flat collapsed cartons delivered with the bottom of the liner tube sealed. In such instances, the flat collapsed tubular carton is then taken from the gluer and passed through a right-angle gluer. In a right angle gluer the carton is fed through the machine in the direction indicated by the directional arrow in Fig. 3. The right-angle gluer first folds back the bottom flaps 31 and 32, as shown in Fig. 3, exposing the bottom of the tubular liner 50 which rests upon the bottom flaps 33 and 34. The bottom seal 72 is then formed by passing the carton under any suitable heat-sealing device, such as a heated narrow-rimmed wheel, for example, substituted for the usual glue wheel in a right-angle gluer. No cut-off device is necessary in this sealing operation. In the particular carton shown, the seal 72 is formed by the heat-sealing device pressing the plies of the liner together against the unfolded bottom flaps. If the bottom flaps do not form a substantially continuous surface under the seal, the heat-sealer for the seam 72 should be equipped with an anvil plate to support the liner during the bottom sealing operation. In the embodiment shown in Fig. 3, the spot of temporary adhesive 68 serves to anchor the forward edge of the under ply of the liner 50 to the flap 34 to prevent rucking.

It will be noted that the bottom sealing seam 72 extends from the central score line to the side score line, which become diagonally opposite corners when the flat collapsed carton is erected. Because the seam 72 will thus extend substantially diagonally across the bottom of the carton when erected, the seal 72 must be spaced below

the bottom fold lines of the carton a sufficient distance to prevent the liner from pulling away from the carton walls when the carton is erected. This distance will vary according to the relative width of the erected carton to its thickness. Thus, with the width of the carton as a and the thickness as b , the distance x from the bottom fold line 13 to the seal 12, as shown in Fig. 3, should be equal to

$$\sqrt{\frac{ab}{2}}$$

To fold the particular carton shown, the user erects the flat collapsed carton and the bottom flaps are sealed or pasted together in the usual manner to form a sealed bottom. The top flaps will then be pulled down in the usual manner, as shown in Fig. 4, to allow the liner mouth to be flattened along the line 73 parallel to the front and back panels for sealing, in any suitable heat-sealer. Because the spots of temporary adhesive 66 and 67, which adhered the forward edge of the liner to the flaps during fabrication, are very weak and designed for temporary adhesion only, the mouth of the liner is separated from the flaps without resistance. After the mouth of the liner is sealed and folded down, the flaps may be closed in the usual manner.

For clarity of illustration, the areas of adhesive 61, 62, 63, and 64 are shown in Fig. 1 as the somewhat conventional heavy rectangular areas of adhesive which adhere the liner sheet to the margins of the panels of the blank. If these areas are as heavy as shown in Fig. 1, the liner 50 will, for all intents and purposes, be permanently secured in the outer carton, since it would be practically necessary to tear the outer carton apart to remove the liner 50. However, just as the small spots or lines of adhesive 66, 67, and 68 will temporarily adhere the liner 50 to the blank 10 during the formation of the lined carton but permit the liner to be readily separated from the flaps after the carton is formed, so may the areas of adhesive 61, 62, 63, and 64 comprise light lines or spots of adhesive which serve as somewhat temporary areas of adhesive to adhere the liner sheet 50 to the blank 10 during the formation of the carton. Thus, after the carton is formed, the liner 50 is not interlocked with the bottom flap or between the glue lap and side panel and, consequently, may be simply pulled out of the carton as a readily separable bag element. When the carton is packed with greasy or pasty materials, it is particularly convenient to be able to separate the liner readily to squeeze out or otherwise remove the greasy or pasty contents.

A package made from my carton is sift-proof, moisture-proof, and even oil-proof, if the liner itself is oil-proof, because all seams in the liner sheet are thoroughly heat-sealed. It will be noted in Fig. 4 that the longitudinal seam 11 and the lateral top heat-seal will have to cross. Because the seam 11 is so fine, however, it will not prevent a secure top heat-seal from being obtained. It does not act as an extra thickness of material as did the seams in the lapped or face-to-face longitudinal seams employed heretofore.

From the foregoing, it is apparent that by my method a lined four-sided carton may be made in standard four-sided carton machinery without substantially altering the machinery itself or the sequence of normal operations. It is also apparent that a carton with a longitudinally seamed liner, made according to my invention, may be more readily handled in automatic carton filling and sealing machinery since my carton liner eliminates the objectionable lap or face-to-face reversely turned fin seams employed heretofore. My invention, therefore, though intended primarily for standard four-sided cartons, may be applied to improve other special types of cartons, such as the so-called "six-sided" cartons, or the like, which must be manufactured on special machinery.

My invention, therefore, is not limited to the particular embodiment disclosed, either in whole or in part, but is limited only to the scope of the following claim. In the claim, the meaning imparted to the terms is to be consistent with the use of the same terms in this specification.

What is claimed is:

In a carton of the class described, a flat tubular four-sided carton blank folded along two parallel longitudinal score lines, a heat-sealable liner sheet adhered to the inner surface of said tubular carton blank, and a longitudinal seam in said liner, said seam being comprised of heat-sealed edges of said liner sheet and located at a fold in said blank, said blank having a second pair of longitudinal score lines parallel to said two score lines and top and bottom fold lines transverse to said score lines, said score lines and said fold lines defining a front panel, a back panel, and two side panels, and a transverse heat-sealed seam extending across said liner parallel to said bottom fold line, said transverse heat-sealed seam being spaced from said bottom fold line at least a distance equal to the square root of one-half the product of the widths of the front panel and the side panel.

HERBERT J. STOTTER.
